UNITED STATES PATENT OFFICE.

EZEKIEL HALL, OF SHARON, MASSACHUSETTS.

DESIGN FOR A SMOKING SET.

46,528.

Specification for Design.

Patented Oct. 13, 1914.

Application filed August 19, 1914. Serial No. 857,604. Term of patent 14 years.

To all whom it may concern:

Be it known that I, EZEKIEL HALL, a citizen of the United States, residing at Sharon, in the county of Norfolk and State of Massachusetts, have invented a new, original, and ornamental Design for Smoking Sets, of which the following is a specification, reference being had to the accompanying drawing, forming a part thereof.

The figure is a perspective view of a smoking set, showing my new design.

I claim:

The ornamental design for a smoking set, as shown.

EZEKIEL HALL.

Witnesses:

JOHN H. LEES,
C. AUERRANO.
